DOOR OPERATING MECHANISM

Julius J. Lawick, Kansas City, Kans.

Application August 30, 1954, Serial No. 452,853

8 Claims. (Cl. 160—188)

This invention relates to new and useful improvements in door operating mechanisms, and has particular reference to an operating mechanism suitable for use in connection with a vertically movable door of the sectional type, such doors being commonly called "overhead" doors and in common usage on garages and the like.

The principal object of the present invention is the provision of a powered door operating mechanism of the class described having incorporated therein a safety device whereby the closing movement of the door is arrested automatically in the event any obstruction is interposed in the path thereof, thereby preventing damage to an automobile, or injury to a person, that may inadvertently be standing in the door opening when the mechanism is actuated to close the door.

Another object is the provision of a door operating mechanism incorporating the safety device as above described, wherein said safety device functions also as a limit control for shutting off the operation of the power unit when the door reaches its normal open and closed positions.

Other objects are simplicity and economy of construction, efficiency and dependability of operation, and adaptability for use in connection with virtually any type of vertically moving door.

With these objects in view, as well as other objects which will appear in the course of the specification, reference will be had to the drawing, wherein:

Fig. 1 is generally an inner face view of a door shown in its closed position and having an operating mechanism embodying the present invention, being a sectional view taken on line I—I of Fig. 2, with parts broken away.

Fig. 2 is a sectional view taken on line II—II of Fig. 1.

Fig. 3 is an enlarged, foreshortened, fragmentary view similar to Fig. 1, showing the door raised slightly from its closed position, and with parts broken away.

Fig. 4 is a fragmentary sectional view taken on line IV—IV of Fig. 3.

Fig. 5 is a fragmentary sectional view taken on line V—V of Fig. 3, with parts left in elevation.

Fig. 6 is a schematic wiring diagram of the operating mechanism.

Like reference numerals apply to similar parts throughout the several views, and the numeral 2 applies to the door opening of a building wall 4, said door opening being provided with a conventional vertically movable door 6 divided horizontally into a plurality of sections 8, 10, 12 and 14, said sections being pivotally joined together by hinges 16. Along its vertical side edges, said door is provided with a plurality of rollers 18 which are engaged in guide tracks 20. Each track 20 has a vertical portion 22 affixed to wall 4 by brackets 24 extending along one side of door opening 2, and a rearwardly extending horizontal portion 26 supported from the building ceiling 28 by hangers 30, said horizontal and vertical portions being connected by a curved portion 32. In opening, the door moves upwardly and rearwardly, rollers 18 being guided in tracks 20, until the door opening 2 is uncovered.

2

The door is operated by an endless cable 34 disposed in a loop which is disposed above, intermediate, and parallel to the horizontal track portions 26. The forward end of said loop is trained over a pulley 36 rotatably mounted in a bracket 38 affixed to wall 4, and the rearward end of said loop is trained over a pulley 40 which is rotatably driven by a gear reduction unit 42 powered by a reversible electric motor 44 mounted on ceiling 28. A link 46 is pivoted at one end, as at 48, to a clamp 50 rigidly fixed on cable 34, and is pivoted as at 52 to a bracket 54 fixed to the uppermost door section 8. Thus when motor 44 is operated in one direction, cable 34 will move clamp 50 rearwardly, pulling link 46 to open the door. When the motor is operated in a reverse direction, the action is reversed to close the door.

A safety rod 56 is disposed adjacent and parallel to the inner face of the door at the lower edge of said door, and is vertically movable with respect to the door. A pair of support rods 58 are each pivotally attached at 20 their lower ends to rod 56, as at 60. Rod 56 extends substantially the full width of the door, and support rods 58 are disposed respectively in oppositely spaced relation from the midpoint of rod 56. Rods 58 extends upwardly, and each is carried for axial sliding movement in holes 62 (Fig. 4) provided therefor in a bracket 64 fixed to the inner surface of lowermost door section 14 by screws 66. Rod 58 extends above bracket 64, and a nut 68 is adjustably threaded thereon to limit the downward movement thereof. When the door is raised, rod 56 falls by 30 gravity until nuts 68 strike brackets 64, in which position rod 56 is disposed below the lower edge 70 of the door, as shown in Figs. 3 and 4. When the door is lowered to its closed position, rod 56 is raised relative to the door by its engagement with the floor 72 beneath the door, to a position flush with the lower edge 70 of the door, as shown in Figs. 1 and 2. Rod 56 will also be raised as described above if, during the closing movement of the door, it should strike a person, vehicle, or other obstruction in its path. If the obstruction should 40 be of limited size, so as for example to engage rod 56 adjacent one end thereof, the rod will tilt about one or the other of pivots 60 of support rods 58. For this reason, the holes 60 of brackets 64 are made sufficiently large to prevent binding of rods 58 therein.

A plurality of switch operating rods 74 are each pivotally attached at their lower ends to rod 56, as at 76. Although the number of such rods is optional, there are three shown in the drawing, one adjacent each end of rod 56 and one at the midpoint thereof. Each operating rod 50 74 extends upwardly into a switch housing 78 mounted on the inner surface of door section 14. Within said housing it extends through a hole 80 (Fig. 3) provided therefor in the free end portion of a tiltable switch support 82 which is pivoted in said housing at 84. A nut 86 adjustably threaded on rod 74 serves to engage and tilt said switch support upwardly when safety rod 56 is raised relative to the door. Said switch support tilts downwardly by gravity when the safety rod is lowered. Suitably mounted on each switch support 82 is a tilt-responsive mercury switch, 60 the three switches being designated respectively by the numerals 88, 90 and 92. Said switches are so disposed that they are closed when their supports 82 and safety rod 56 are lowered, and open when said supports and safety rod are raised. Carried also in one of housing 78, the central housing as shown, is a fourth tilt-responsive switch 94. As shown in Figs. 3 and 5, said switch is disposed in an inclined position in a vertical plane at right angles to the plane of the door. Its inclination is such that it will be closed when the door is in its normal vertical position, but will be tilted to open when the door section 14 to which it is attached is tilted out of a vertical plane.

as the door is opened. Section 14 is the last section to be tilted toward a horizontal plane as the door opens. Switch 94 is carried by a bendable support 96 mounted in housing 78. By bending said support, the inclination of switch 94 may be adjusted, so as to vary the angle to which door section 14 must be tilted to open the switch.

Referring to Fig. 6, it will be seen that operating current for motor 44 is drawn from line wires 98 and 100 through wires 102 and 104 to a double-pole, double-throw switch 106. Said switch is manually reversible to feed current to motor 44 either through wires 108 and 110 to operate said motor in one direction to raise the door, or through wires 112 and 114 to operate the motor in a reverse direction to lower the door. The internal wiring of the motor is conventional and is not here shown. Wire 102 is provided with a normally open push button switch 116, and wire 104 has a normally closed push button switch 118 therein. In a by-pass circuit around switch 116, there are connected in series a wire 120, switch 92, wire 122, switch 94, wire 124, switch 90, wire 126, switch 88, and wire 128. Thus all of the mercury switches 88, 90, 92 and 94 are connected in series to by-pass switch 116, or switch 116 may be said to by-pass the mercury switches. The wires to the various tilt-responsive switches are disposed in conduits 130 suitably affixed to the inner surface of the door. The connections from the tilt-responsive switches to the motor and other stationary parts of the system are made through a flexible cable or other suitable means, not shown, which will not interfere with the movement of the door.

In operation, assuming that the door is closed as shown in Figs. 1 and 2, switch 94 will be closed, but switches 88, 90 and 92 will be open, due to the fact that safety rod 56 has been raised relative to the door by its contact with the floor. To raise the door, the operator first sets selector switch 106 to deliver current to the motor through wires 108 and 110, then closes switch 116 momentarily. This starts the door upwardly. As the door rises the first inch or two, safety rod 56 drops by gravity below the lower edge of the door, permitting switches 88, 90 and 92 to close. This completes the by-pass circuit around push button 116, and said push button may then be released. The door will then continue to rise until the lowermost section 14 thereof is tilted out of its normal vertical plane by the curved portions of tracks 20. This tilting action opens switch 94, thus interrupting the motor circuit and bringing the system to rest. At this time switches 88, 90 and 92 are closed, and switch 94 is open. To close the door, the operator first reverses the switch 106 to deliver current to the motor through wires 112 and 114, then depresses push button 116 momentarily. This completes the motor circuit, and the door starts downwardly. As soon as door section 14 is disposed vertically, or nearly so, switch 94 is closed, thereby completing the by-pass circuit around switch 118, and switch 116 may then be released. The door then normally continues its downward movement until safety rod 56 strikes floor 72 and is thereby raised relative to the door to operate through control rods 74 to open switches 88, 90 and 92, thereby interrupting the motor circuit and bringing the system to rest. The "over travel" of the door, that is, the distance it will travel or "coast" after the current has been shut off, may be provided for by adjusting nuts 86 along rods 74 whereby to open switches 88, 90 and 92 before the door is completely closed. The over-travel will then carry the door to its completely closed position against the floor.

However, if during the closing motion of the door it should encounter an obstruction, such as a person standing in the door opening or a vehicle parked there, said obstruction will be first engaged by safety rod 56, and said safety rod will be forced upwardly relative to the door. If the obstruction is of limited width as compared to the door, safety rod 56 will tilt relative to the door, on one or the other of pivots 60. In any event, however, at least one of switches 88, 90 or 92 will thereby be opened, inter-

rupting the motor circuit and bringing the system to rest to prevent injury or damage to the obstruction. Push button 118 may be depressed at any time during the operation of the door, in order to stop the movement of the door whenever desired.

It is apparent that if the safety rod 56 were perfectly rigid, only the switches 88 and 92 at the ends of said rod would be required, since no matter where an obstruction contacted the rod, one end of said rod would necessarily be raised. However, it is desirable that the safety rod be small and light, and it of course must be substantially as long as the door is wide, which may be eight or ten feet in ordinary installations. Hence the rod is of necessity somewhat flexible, and might be flexed upwardly by an obstruction striking its mid-portion without raising its ends. For this reason the central switch 90 has been added. On very wide doors, additional intermediate switches might be required.

While I have shown and described a specific embodiment of my invention, it is apparent that many minor changes of structure and operation could be made without departing from the spirit of the invention as defined by the scope of the appended claims.

What I claim as new and desire to protect by Letters Patent is:

1. In combination with a vertically movable door, power means including a reversible electric motor operable to raise and lower said door, a plurality of vertical support rods disposed vertically and carried for limited axial sliding movement by said door adjacent the lower edge thereof, and adapted when in their lowermost position to depend by gravity below the lower edge of said door, a safety rod parallel to the lower edge of said door and extending substantially the full width thereof, each of said support rods being attached pivotally at its lower end to said safety rod on a horizontal axis at right angles to the plane of the door whereby to support said safety rod, a plurality of safety switches mounted on said door and connected in series in the operating circuit of said motor, and a plurality of operating rods each pivoted at its lower end to said safety rod on an axis parallel to the pivotal connections of said support rods and each operatively connected to one of said safety switches whereby to close said switch when said safety rod is lowered and to open said switch when said safety rod is raised.
2. A device as set forth in claim 1 wherein said safety switches are tilt-responsive and are pivotally carried by said door and normally urged toward their closed positions by gravity, and wherein said operating rods function to tilt said switches to their open positions whenever said safety rod is raised relative to said door.
3. A device as set forth in claim 1 with the addition of a conductor by-passing all of said safety switches in the motor operating circuit, and a starting switch in said conductor.
4. In combination with a horizontally sectioned, normally vertical door which moves vertically to and from its closed position, and the sections of which successively tilt out of a vertical plane as said door is raised, power means including a reversible electric motor operable to raise and lower said door, and a tilt-responsive limit switch disposed in the operating circuit of said motor and mounted on the lowermost section of said door, said switch being disposed to remain closed so long as said door section remains vertical, and to open when said door section tilts toward a horizontal plane.
5. In combination with a horizontally sectioned, normally vertical door which moves vertically to and from its closed position, and the sections of which successively tilt out of a vertical plane as said door is raised, power means including a reversible electric motor operable to raise and lower said door, an electric safety switch disposed in the operating circuit of said motor, said switch being mounted on said door, a safety member carried by said door for limited vertical movement relative thereto,

said safety member being adapted to depend below the lower edge of said door by gravity when said door is raised and to be moved upwardly relative to said door by engagement with the floor beneath said door as said door approaches its closed position, an operative connection between said safety member and said safety switch, whereby said switch is closed when said safety member is lowered and opened when said safety member is raised, and a tilt-responsive limit switch disposed in the operating circuit of said motor in series with said safety switch, and mounted on the lowermost section of said door, said switch being adapted to remain closed so long as said door section remains vertical, and to open when said door section tilts toward a horizontal plane.

6. A device as set forth in claim 5 with the addition of a conductor by-passing both the safety and limit switches in said motor circuit, and a starting switch in said conductor.

7. In combination with a vertically movable door, power means including a reversible electric motor operable to raise and lower said door, a plurality of safety switches mounted on said door in spaced relation adjacent the lower edge thereof, said switches all being connected in series in the operating circuit of said motor, a safety rod carried by said door parallel to the lower edge thereof and mounted for limited vertical and tilting movement with respect thereto, said safety rod being adapted to depend below the lower edge of said door by gravity when said door is raised and to be moved upwardly rela-

tive to said door by engagement with the floor beneath said door as said door approaches its closed position and an operative connection beneath said safety rod and each of said switches, whereby said switch is closed when said safety rod is lowered and opened when said safety rod is raised.

8. In combination with a vertically movable door, power means including a reversible electric motor operable to raise and lower said door, a tilt-responsive electric safety switch disposed in the operating circuit of said motor and pivotally mounted on said door, said switch being normally tiltable by gravity to a closed position, a rigid safety member carried by said door for limited vertical movement relative thereto, said safety member being adapted to depend below the lower edge of said door by gravity when said door is raised and to be moved upwardly relative to said door by engagement with the floor beneath said door as said door approaches its closed position, and an operative connection between said safety member and said safety switch and operable to tilt said switch to an open position as said safety member is raised relative to said door.
